M. R. BASS & W. A. ALEXANDER.

CUE RACK.

APPLICATION FILED JULY 19, 1911.

1,007,414.

Patented Oct. 31, 1911.

UNITED STATES PATENT OFFICE.

MORRIS R. BASS AND WILLIAM A. ALEXANDER, OF BOSTON, MASSACHUSETTS.

CUE-RACK.

1,007,414.

Specification of Letters Patent. Patented Oct. 31, 1911.

Application filed July 19, 1911. Serial No. 639,434.

To all whom it may concern:

Be it known that we, MORRIS R. BASS and WILLIAM A. ALEXANDER, citizens of the United States, and residents of Boston, in the county of Suffolk and State of Massachusetts, have invented a new and Improved Cue-Rack, of which the following is a full, clear, and exact description.

The object of our invention is to provide a cue rack, so constructed as to provide for imparting longitudinal compression to the cue while in the rack, for repairing the tips of the cues, and at the same time to so support the cues, while under longitudinal compressive action, as to prevent lateral or side-wise movement of the cues; and to further provide a cue rack of ornamental appearance, which will safely hold the cues when inserted therein, and prevent their withdrawal without the consent of the user or owner of the cues.

Reference is to be had to the accompanying drawings forming a part of this specification, in which the same characters of reference indicate the same parts in all the views.

Figure 1 shows a front perspective view of a cue rack embodying our invention; Fig. 2 shows in side elevation one of the tip clamps, the lower end of the clamp being in section to show the socket; Fig. 3 shows a top plan view of one of the locking braces; and Fig. 4 shows a detail of one of the rests for the butt of the cue.

Our improved cue rack comprises a back-board A, which may be made of any suitable material and ornamented in any desired manner. Extending across the front of the back-board A and near its lower end and projecting at right-angles therefrom is a shelf B, preferably supported by means of brackets b. In the upper surface of the shelf B are seats or sockets b' of a size to receive the butt ends of the cues.

At or near the upper end of the back-board A are metallic brackets C, projecting therefrom at right-angles to the surface of the board, and being formed integral with a plate c, which is secured to the board A by means of screws c'. There are as many of these brackets C as there are sockets b' in the shelf B; and these brackets C are preferably arranged in horizontal alinement and directly over and in vertical alinement with the respective socket b' with which it is to coöperate. The brackets C at their outer

ends receive a threaded bolt D, which, at its upper end, is provided with a winged head d, and at its lower end with an enlargement d', having in its under face a tip socket d''. 60

It will be understood that, with the butt of the cue seated in one of the sockets b', and its top brought into alinement with the socket d'', the turning of the bolt D in its threaded bearing in the bracket C, causes a longitudinal compressive force to be imparted to the cue, thus locking the cue in place in the rack and supplying the necessary pressure to repair the tip. In order to prevent the cues from springing sidewise during this longitudinal pressure, there are provided locking braces E, extending across the back-board A in horizontal alinement with each other, there being one such brace for each cue-engaging rest and clamp. 70 These locking braces comprise a block e, which is fastened to the base-board A, and which at its front face is provided with a semi-circular notch e'. Coöoperating with the block e there is a swinging block e'', 80 which has in its inner face a semi-circular notch e''. The block e'' is hinged at one end by means of a hinge H, so that it may swing toward and from the block e, as shown in dotted lines in Fig. 3. When closed, the mating notches e' and e'' form a circular opening to receive and embrace the cue between the butt and the tip. The swinging block e'' is held in its closed position by means of a swinging bail K, having a slot to engage a hasp K' attached to the edge of the block e''. The hasp K' may receive a lock, whereby the locking brace may be locked and thus prevent the unauthorized removal of the cue. 90

In order to insure that even though the cue be released from its clamp D, it may not be removed from the rack, there will be provided a guard-board M at the upper end of the rack and projecting therefrom at right-angles to the back-board A, and above but relatively close to the line of tip clamps. 100

It is of course understood that while we have shown in the drawing a rack embodying six cue-clamping and retaining devices, we are not limited to any particular number, as they may be made to hold a single cue or more than six, as circumstances may require. 105

Having thus described our invention, we claim as new and desire to secure by Letters Patent:

A cue rack comprising a back board, a fixed rest, a socket therein for the butt of the

cte, a bracket on the back board above the fixed rest, a socketed clamp for the tip of the cue supported by said bracket in line with the socket for the butt of the cue, a brace located between the rest and clamp, and comprising a block attached to the back board and having a notch in its front edge, and a swinging block pivoted to the first block and having a mating notch in its inner edge,
10 means for moving the socketed clamp to en-

gage the tip of the cue, and a guard above and closely adjacent the socketed clamp.

In testimony whereof we have signed our names to this specification in the presence of two subscribing witnesses.

MORRIS R. BASS.

WILLIAM A. ALEXANDER.
